ADJUSTABLE THERMOSTAT

Charles S. Mertler, Mansfield, Ohio, assignor to Stevens Manufacturing Company, Inc., a corporation of Ohio

Application June 8, 1954, Serial No. 435,179

16 Claims. (Cl. 200—139)

The invention relates in general to adjustable thermostats and more particularly to an improved adjusting screw for more consistent calibration of the adjustable positions of a thermostat.

Adjustable thermostats for controllable electrical devices have been used for many years with the thermostat containing a bimetallic element or other heat responsive means which controls the opening and closing of electrical contacts to control the application of electric energy to the electrical device, such as a household appliance. Such adjustable thermostats include some form of adjusting screw bearing upon or acting upon a movable contact carrying member, generally a resilient spring operated member. Such contact carrying member is quite frequently made of stainless steel to resist corrosion in the heated environment of the thermostat. The adjusting screw must act upon this stainless steel member, and in most applications the adjusting screw is threadably carried in some manner by the base or frame of the thermostat and generally it must be electrically insulated from the contact carrying member. This is for general safety purposes as well as fulfilling the requirements of the electrical appliance manufacturer.

For many years it has been customary to utilize a porcelain bar with a generally pointed end carried by the adjusting screw and with the pointed end bearing against the stainless steel contact carrying member. The stainless steel member and pointed porcelain bar thus in the past have had high per unit area pressures at the point of mutual contact since the contact carrying member is under rather high initial stress to make sure that the contacts will open and close properly under all temperature conditions. Stainless steel is a generally poor bearing material and porcelain is generally abrasive and thus the high per unit area pressure therebetween has frequently caused a chipping of the area around the point on the porcelain bar. This chipping causes very serious abrasion once it occurs to thus further damage the stainless steel contact carrying member and the porcelain bar.

In practically all household electrical appliances the adjusting screw is calibrated for temperature and this chipping and/or abrasion between the stainless steel member and porcelain bar seriously changes the preset calibration. When this occurs, the electrical appliance no longer operates satisfactorily as far as the user is concerned; and therefore, the user becomes dissatisfied with the appliance. For this reason electrical appliance manufacturers are extremely desirous of obtaining thermostats which maintain their initial calibration throughout the useful life of the thermostat.

It is accordingly an object of this invention to provide a thermostat maintaining uniform calibration throughout the life of the thermostat.

Another object of the invention is to provide a thermostat which resists wear and breakage on the operating parts.

Another object of the invention is to provide a metal-

2

to-metal bearing engagement between wearing parts of the thermostat.

Another object of the invention is to provide convex engaging surfaces on the wearing parts of a thermostat. 5 Still another object of the invention is to provide an adjusting screw which is insulated from a contact carrying member with the insulation provided by a part of the adjusting screw and with this insulation not forming any part of the relatively rotatable portions of the thermostat which achieve the variations in adjustment positions.

Still another object of the invention is to provide an adjusting screw for a thermostat wherein the error of calibration is lessened and is less dependent upon tolerance between fitted parts.

Other objects and a fuller understanding of this invention may be had by referring to the following description and claims, taken in conjunction with the accompanying drawings, in which:

20 Figure 1 is a side elevational view of a thermostat embodying the invention;

Figure 2 is a similar side view of the thermostat in a different adjustment position;

Figure 3 is an enlarged sectional view through the adjusting screw of the thermostat; and

Figure 4 is a view similar to Figure 3 but showing a prior art form of the device.

The Figures 1, 2, and 3 show the improved form of adjusting screw utilized in the thermostat of the invention. The thermostat is indicated generally by the reference numeral 11 and includes a base 12 and a stack 13. The base 12 carries a nut 14 which has a neck portion 15 passing through an aperture 16 in the base 12. The lower end 17 of the neck 15 is swaged outwardly to fasten the nut 14 firmly onto the base 12. A composite adjusting screw 20 threadably engages the nut 14. The adjusting screw 20 cooperates with and moves a contact carrying member 21. This contact carrying member 21 is carried in the stack 13 as is a second contact carrying member 22 and a bimetallic strip 23. The members 21 and 22 and strip 23 are mounted in the stack 13 by a headed hollow rivet 24 with insulating washers 25 insulating the parts 21, 22, and 23 from each other and from the rivet 24. Terminal lugs 26 and 27 are respectively in electrical contact with the contact carrying members 21 and 22.

The bimetallic strip 23 carries a porcelain button 30 so that when the bimetallic strip 23 is moved upwardly by temperature changes as shown in Figure 2, the button 30 may contact and move the contact carrying member 22. The contact carrying members 21 and 22 carry first and second contacts 31 and 32, respectively.

The thermostat 11 is representative of many forms of generally used thermostats with which the adjusting screw 20 of this invention may be used. The Figure 3 shows to an enlarged scale the details of construction of the adjusting screw 20. The screw 20 has male threads 35 to be received in the nut 14. A surface 36 in the screw 20 defines a first axial cavity. A hollow porcelain tube 37 is received preferably with close clearance in the cavity 36.

60 The outside diameter of the porcelain tube 37 may be closely dimensioned by centerless grinding methods so that it has very close tolerance with the axial cavity 36. A surface 38 defines a second axial cavity which is the longitudinal bore in the tube 37. The tube 37 has lower and upper ends 39 and 40, respectively, and both of these ends are preferably normal to the axis of the tube 37 which provides ease and cheapness of manufacture.

A steel pin 42 is carried in the lower end 39 of the tube 37. The pin 42 has a shank 43 and a rounded head 44. The shank 43 may be cemented into the bore 38 by cement 45 or alternatively the cement 45 may be

eliminated if a sufficiently close fit is provided between the shank 43 and the bore 38. The head 44 has a flat underside 46 which abuts the flat face on the lower end 39 of the tube 37. This provides a relatively large and good bearing surface between the steel pin 42 and the porcelain tube 37. The head 44 of the pin is hardened, and in practice because of the small size, this means that the entire pin 42 is hardened.

An additional feature of the thermostat 11 may be provided; namely, a trim screw 49 for adjustment of the thermostat calibration in the field. The trim screw 49 is axially aligned with the screw 20 and extends through a threaded aperture 50 from the top of the screw 20 with the screw 49 in engagement with the upper flat face 40 of the porcelain tube 37. The diameter of the screw 49 is greater than the diameter of the bore 38 yet less than the diameter of the cavity 36, in order to permit movement of the screw 49 into the cavity 36.

Operation

The adjusting screw 20 is a principal feature of the invention in that it eliminates the former problems of a rotatable porcelain member bearing directly upon a contact carrying member. This prior art construction is shown in Figure 4 wherein a rotatable porcelain bar 52 having a relatively sharp point 53 rotated and bore against a spring contact member 21A which would be similar to the member 21 in Figures 1 to 3. In this prior art construction of Figure 4 high unit area pressures were established at the point 53 and a bearing portion 54 on the spring contact member 21A. The Figure 1 shows the thermostat under adjustment conditions indicating a high temperature setting, assuming that the bimetallic strip 23 moves upwardly with increasing temperature. The Figure 2 shows the same thermostat adjusted for considerably lower temperature conditions. A comparison of Figures 1 and 2 will show that the contact carrying member 21 initially must have a high degree of set in the upwardly directed position in order to maintain satisfactory contact pressure between the contacts 31 and 32 in the high temperature adjustment position shown in Figure 1. However, when the thermostat is adjusted for lower temperature conditions as in Figure 2, the adjusting screw 20 must overcome a considerable amount of upward force as generated by the greatly deflected contact carrying member 21. This is shown enlarged in Figure 3. A similar position of the contact carrying member 21A is shown in Figure 4 and thus it will be realized that high per unit area pressures are encountered between the point 53 and the bearing portion 54.

In Figure 3 the rounded head 44 has a convex face 55 which provides a greatly enlarged bearing means for cooperation with a corresponding bearing portion 56 on the contact carrying member 21. Thus, it will be seen that the combination of the bearing means or rounded face 55 and the bearing portion 56 establishes convex cooperating surfaces to thus provide a greatly improved bearing condition between the adjusting screw 20 and the member 21.

Still further, the rounded head 44 is hardened steel so that in cooperation with the stainless steel contact carrying member 21 there are two hard metals providing the bearing surface which is considerably superior to the porcelain bar 52 in contact with the member 21A as in Figure 4. In the prior art construction in Figure 4 it was found that frequently a chip would break off the point 53 which would quickly abrade the bearing portion 54 to rapidly destroy the calibration of the thermostat. In Figure 1 a pointer 58 has been more or less diagrammatically indicated with the pointer cooperating with a dial or scale 59. This pointer and scale 58 and 59 are generally provided by the electrical appliance manufacturer who incorporates the thermostat 11 into the appliances manufactured. Such electrical appliance manufacturer naturally desires that the thermostat 11 maintain a constant calibration throughout its useful life, and any

chipping and abrading of the sharp point 53 in Figure 4 would rapidly destroy this calibration. The present invention of the steel pin 42 eliminates this problem and provides good bearing surfaces which maintain constant calibration of the adjusting screw or stud 20.

The flat faces 39 and 40 on the porcelain tube 37 make these tubes easy to manufacture and provide a good bearing surface both with the adjusting screw 20 and trim screw 49, if used, and the underside of the head 44. Also, the outside diameter of the porcelain tube 37 may be manufactured to a given diameter with close tolerances so that the tube 37 fits closely within the cavity 36. This eliminates much of the sloppiness of fit formerly encountered which also tended to destroy accurate calibration.

Although this invention has been described in its preferred form with a certain degree of particularity, it is understood that the present disclosure of the preferred form has been made only by way of example and that numerous changes in the details of construction and the combination and arrangement of parts may be resorted to without departing from the spirit and the scope of the invention as hereinafter claimed.

What is claimed is:

1. An adjustment mechanism for a spring contact member insulatively carried on the base of a thermostat, comprising, a male threaded stud threadedly carried by said base, bearing means cooperating with a bearing portion on said spring contact member, one of said bearing means and said bearing portion having a convex face, a body disposed between said bearing means and said stud, and one of said stud, body, bearing means, and bearing portion being of insulating material to move said contact member relative to said base upon rotation of said stud.

2. An adjustment mechanism for a spring contact member insulatively carried on the base of a thermostat, comprising, a male threaded stud threadedly carried by said base, bearing means cooperating with a bearing portion on said spring contact member, one of said bearing means and said bearing portion having a convex face, and insulating means supporting said bearing means from said stud to move said contact member relative to said base upon rotation of said stud.

3. An adjustment mechanism for a spring contact member insulatively carried on the base of a thermostat, said mechanism comprising, a male threaded stud threadedly carried by said base, a surface defining an axial cavity in the lower end of said stud, a tube closely fitting within said cavity and having a lower end extending out of said cavity, a pin having a rounded head and a shank, said shank closely fitting in the bore of said tube and said pin being carried in the lower end of said tube with the underside of said head engaging the end of said tube, the rounded side of said head engaging said spring contact member upon rotation of said stud in said nut to move said contact member relative to said base, and one of said head, shank, tube and stud being formed of insulating material to insulate said spring contact member from said base.

4. An adjustment mechanism for a spring contact member carried on the base of a thermostat, said adjustment mechanism comprising, a male threaded stud threadedly carried by said base, a surface defining an axial cavity in the lower end of said stud, an insulated member fitting within said cavity and having a lower end extending out of said cavity, a hardened steel element having a rounded face, a part of said element fitting in the bore of said insulated member, and said face engaging said spring contact member upon rotation of said stud in said face to move said contact member relative to said base.

5. A thermostat comprising, a base, a spring contact member carried on said base, a nut fixedly carried on said base, a male threaded stud threadedly carried through said nut, a surface defining an axial cavity in the lower end of said stud, a porcelain body closely fitting within said cavity and having a lower end extending out of said cavity, a second cavity in said porcelain body, a metallic element disposed in said second cavity, a rounded face on said

metallic element engaging said spring contact member upon rotation of said stud in said nut to move said contact member relative to said base, a coaxial tapped hole in said stud extending from the top end thereof to said axial cavity, the diameter of said tapped hole being less than that of said first axial cavity, and an adjustment screw threaded in said tapped hole and bearing against the top end of said porcelain body for axial adjustment thereof relative to said stud.

6. A thermostat comprising, a base, a spring contact member carried on said base, a nut fixedly carried on said base, a male threaded stud threaded through said nut, a surface defining an axial cavity in the lower end of said stud, a porcelain body closely fitting within said cavity and having a lower end extending out of said cavity, a second cavity in said porcelain body, a metallic element disposed in said second cavity, and a rounded face on said metallic element engaging said spring contact member upon rotation of said stud in said nut to move said contact member relative to said base.

7. A thermostat comprising, a base, a spring contact member carried on said base, a nut fixedly carried on said base, a male threaded stud threaded through said nut, a surface defining an axial cavity in the lower end of said stud, an insulated tube closely fitting within said cavity and having a lower end extending out of said cavity, a hardened steel pin having a rounded head and a shank, said shank closely fitting in the bore of said tube and the underside on said head engaging the end of said tube, and said head engaging said spring contact member upon rotation of said stud in said nut to move said contact member relative to said base.

8. A thermostat comprising, a base, a spring contact member carried on said base, a nut fixedly carried on said base, a male threaded stud threaded through said nut, a surface defining an axial cavity in the lower end of said stud, an electrically insulated tube closely fitting within said cavity and having a lower end extending out of said cavity, a hardened steel pin having a rounded head and a shank, said shank closely fitting in the bore of said tube and said pin being cemented in the lower end of said tube with the underside of said head engaging the end of said tube, and said head engaging said spring contact member upon rotation of said stud in said nut to move said contact member relative to said base.

9. An adjusting screw for a thermostat and adapted for threaded connection with the thermostat to provide adjustable movement of a spring contact member carried by said thermostat, said screw comprising, a surface defining an axial cavity in the lower end of said screw, a porcelain tube closely fitting within said cavity and having a lower end extending out of said cavity, a flat face on the lower end of said tube generally normal to the axis thereof, a hardened steel pin having a head and a shank, said shank closely fitting in the bore of said porcelain tube and said pin being cemented in the lower end of said tube with the underside of said head engaging said flat face, said head engageable with said spring contact member upon rotation of said screw in said thermostat to move said contact member relative to said thermostat, and said head being rounded to thus maintain substantially constant temperature calibration throughout the life of said thermostat.

10. A thermostat comprising, a base, a spring contact member carried on said base, a nut staked to said base, a male threaded stud threaded through said nut, a surface defining an axial cavity in the lower end of said stud, a porcelain tube closely fitting within said cavity and having a lower end extending out of said cavity, a flat face on the lower end of said tube generally normal to the axis thereof, a hardened steel pin having a head and a shank, said shank closely fitting in the bore of said porcelain tube and said pin being cemented in the lower end of said tube with the underside of said head engaging said flat face, said head engaging said spring contact member upon rotation of said stud in said nut

to move said contact member relative to said base, and said head being rounded to thus maintain substantially constant temperature calibration throughout the life of said thermostat.

5 11. An adjusting screw for a thermostat and adapted for threaded connection with the thermostat to provide adjustable movement of a spring contact member carried by said thermostat, said screw comprising, a surface defining an axial cavity in the lower end of said screw,

10 a porcelain tube closely fitting within said cavity and having a lower end extending out of said cavity, a flat face on the lower end of said tube generally normal to the axis thereof, a hardened steel pin having a head and a shank, said shank closely fitting in the bore of said porcelain tube and said pin being cemented in the lower end of said tube with the underside of said head engaging said flat face, said head engageable with said spring contact member upon rotation of said screw in said thermostat to move said contact member relative to said

20 thermostat, said head being rounded to thus maintain substantially constant temperature calibration throughout the life of said thermostat, a coaxial tapped hole in said screw extending from the top end thereof to said axial cavity, the diameter of said tapped hole being less than that of said axial cavity and greater than that of said porcelain tube bore, and an adjustment screw threaded in said tapped hole and bearing against the top end of said porcelain tube for axial adjustment thereof relative to said screw.

30 12. A thermostat comprising, a base, a spring contact member carried on said base, a nut staked to said base, a male threaded stud threaded through said nut, a surface defining an axial cavity in the lower end of said stud, a porcelain tube closely fitting within said cavity and having

35 a lower end extending out of said cavity, a flat face on the lower end of said tube generally normal to the axis thereof, a hardened steel pin having a head and a shank, said shank closely fitting in the bore of said porcelain tube and said pin being cemented in the lower

40 end of said tube with the underside of said head engaging said flat face, said head engaging said spring contact member upon rotation of said stud in said nut to move said contact member relative to said base, said head being rounded to thus maintain substantially constant temperature calibration throughout the life of said thermostat,

45 a coaxial tapped hole in said stud extending from the top end thereof to said axial cavity, the diameter of said tapped hole being less than that of said axial cavity and greater than that of said porcelain tube bore, and an adjustment screw threaded in said tapped hole and bearing against the top end of said porcelain tube for axial adjustment thereof relative to said stud.

55 13. An adjustment mechanism for a movable member carried on the base of a thermostat, comprising, a threaded stud threadedly carried by said base, a bearing portion on said movable member, bearing means on said stud and cooperating with said bearing portion, one of said bearing means and said bearing portion having a convex face, one of said stud, bearing means and bearing portion being of insulating material, and said cooperation between said bearing means and bearing portion providing movement to said member relative to said base upon rotation of said stud.

60 14. An adjustment mechanism for a movable member carried on the base of a thermostat, comprising, an axially movable stud movably carried by said base, a bearing portion on said movable member, bearing means on said stud, one of said bearing means and said bearing portion having a convex face, one of said stud, bearing means and bearing portion being of insulating material, and means for providing physical cooperation between said bearing means and bearing portion to move said member relative to said base upon axial movement of said stud.

65 15. An adjustment mechanism for a spring member carried on the base of a thermostat, comprising, an axial-

ly movable stud movably carried by said base, bearing means physically cooperating with a bearing portion on said spring member, one of said bearing means and said bearing portion having a convex face, and insulating means supporting said bearing means from said stud to move said contact member relative to said base upon axial movement of said stud.

16. An adjustment mechanism for a movable member carried on the base of a thermostat, said adjustment mechanism comprising, an insulated member having a

boré, a hardened steel element having a rounded face, a part of said element fitting in the bore of said insulated member, said face being engageable with said movable member, and means for providing axial movement of said insulated member relative to said base to move said movable member relative to said base.
